(57) **CLAIM**

The ornamental design for partially transparent IC card, as shown and described.

DESCRIPTION

FIG. 1 is an enlarged top, front and right side perspective view of partially transparent IC card showing our new design; FIG. 2 is a top plan view thereof; FIG. 3 is a front elevational view thereof; FIG. 4 is a rear elevational view thereof; FIG. 5 is a right side elevational view thereof; FIG. 6 is a left side elevational view thereof; FIG. 7 is a bottom plan view thereof; and, FIG. 8 is a greatly enlarged cross-sectional view thereof taken along line 8—8 in FIG. 2. The phantom line showing in the drawings is for illustrative purposes only and forms no part of the claimed design.
